Des. 203,824

Patented Feb. 22, 1966

203,824

CABINET FOR ELECTRICAL INSTRUMENTS OR THE LIKE

Paul O. Rawson, Trumbull, and George L. Schick, New Canaan, Conn., assignors to The Singer Company, New York, N.Y., a corporation of New Jersey

Filed Nov. 6, 1964, Ser. No. 82,500

Term of patent 14 years

(Cl. D26—1)

Fig. 1.

Fig. 2.

FIG. 1 is a front perspective view of a cabinet for electrical instruments or the like, showing our new design; and

FIG. 2 is a rear perspective view of the cabinet for electrical instruments or the like shown in FIG. 1.

The essential features of our design are shown in full lines in the drawings.

The side not shown is substantially a mirror image of the side shown.

We claim:

The ornamental design for a cabinet for electrical instruments or the like, substantially as shown and described.
